(57) **CLAIM**

The ornamental design for a LED third brake lamp, as shown and described.

DESCRIPTION

FIG. 1 is a first perspective view of a LED third brake lamp showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the LED third brake lamp thereof;

FIG. 10 is a sectional drawing of FIG. 3; and,

FIG. 11 is an enlarged view of the selected portion 11 in FIG. 1.

The broken lines shown in the drawings depict portions of the LED third brake lamp that form no part of the claimed design.
